(57) **CLAIM**

The ornamental design for a back cover for a bumper case, as shown and described.

DESCRIPTION

FIG. 1 is a front perspective view of a back cover for a bumper case showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a sectional view taken in the direction of line 9-9 of FIG. 3;

FIG. 10 is a sectional view taken in the direction of 10-10 of FIG. 3;

FIG. 11 is a sectional view taken in the direction of 11-11 of FIG. 3; and,

FIG. 12 is a sectional view taken in the direction of 12-12 of FIG. 3.

The evenly dashed broken lines, and unshaded regions bounded by broken lines, depict portions of the back cover for a bumper case that form no part of the claimed design. The dot-dashed broken lines are included for the purpose of defining the bounds of the claimed design and form no part of the claimed design.

The broken lines crossing over the article in FIG. 3, are included for the purpose of illustrating the sources of the sectional views and form no part of the claimed design.
